[57] **CLAIM**

The ornamental design for a pair of motorcycle fairing edge guards, as shown and described.

DESCRIPTION

FIG. 1 is a top plan view of a pair of motorcycle fairing edge guards showing the new design.

FIG. 2 is a top plan view of the left motorcycle fairing edge guard shown separately for convenience of illustration.

FIG. 3 is a bottom plan view of FIG. 2.

FIG. 4 is a first side elevation view of FIG. 2.

FIG. 5 is a second side elevation view of FIG. 2.

FIG. 6 is a rear elevation view of FIG. 2; and,

FIG. 7 is a front perspective view of FIG. 2.

The right motorcycle fairing edge guard is a mirror image of the left motorcycle fairing edge guard and is not illustrated in detail.
